UNWINDER AND WINDER MECHANISM FOR
PAPER MACHINERYCharles P. Putnam, Lockhaven, Pa., assignor to
Beloit Iron Works, Beloit, Wis., a corporation of
Wisconsin

Application September 27, 1934, Serial No. 745,659

37 Claims. (Cl. 92—73)

This invention relates to unwinding and winding mechanism, and has special reference to such mechanism designed particularly for use with paper machinery, though not necessarily limited exclusively to such application.

In the operation of paper working machinery of the character used for making, treating, or finishing paper in which a continuous sheet of paper must be rolled up as it comes from the machine or unrolled as it is fed to the machine, it has been customary to employ winding or unwinding mechanism, as the case may be, located adjacent the machine, the sheet being unsupported in a so-called draw between the machine and the winder or unwinder. This arrangement is beset by a number of serious disadvantages, and a primary object of this invention is to overcome in a large measure these objectionable characteristics.

Among the more important objects of the invention are the following:

(1) To eliminate the long draws to and from the paper working machinery, and to eliminate the breaks in the sheet resulting from such draws.

(2) To eliminate the dance rolls, spreaders, and similar devices for keeping the sheet taut and free from wrinkles in the draws and other associated mechanism.

(3) To increase the speed of operation of the paper working machinery by increasing the rate at which the sheet may be fed to and removed from the machine.

(4) To provide better control over the hardness of the roll and the winding of the sheet.

(5) To increase the ease of charging and discharging the rolls of paper.

(6) To eliminate the difficulty in synchronizing the speed of the winder or unwinder with the speed of the paper working machine with which the winder is used.

(7) To provide a more compact machine occupying a minimum amount of floor space.

I have aimed to provide unwinding and winding means for supercalenders arranged to materially increase the operating speed of the machine.

Another object of the invention is to provide winding mechanism operated directly against the rolls of the machine with which they are employed, whereby the sheet is supported against the surface of a roll at all times, thereby entirely eliminating the conventional draw and the objectionable features associated therewith.

A further object of the invention is the provi-

sion of winding mechanism wherein the roll of paper is driven directly by contact against the roll of the machine with which it is employed.

I have also aimed to provide mechanism of the class described having improved means to regulate the pressure between the rolls during the handling of a roll of paper.

Another object of the invention is the provision of a supercalender having winding means operating in surface contact with a calender roll at the offgoing end of the machine, and means for supporting a roll of paper at the opposite end of the machine in such proximity to the adjacent roll as to eliminate or substantially eliminate the draw in the sheet.

Other objects and advantages will be apparent from the following description and the accompanying drawings, in which—

Figure 1 is a side view of a supercalender embodying my invention;

Fig. 2 is a face view of a winder embodying my invention showing the lower end of a supercalender stack in section;

Fig. 4 is a section on the line 4—4 of Fig. 2;

Fig. 5 is a section similar to Fig. 4 showing the parts in a moved position;

Fig. 6 is a side view of my unwind mechanism as applied to a supercalender showing a full roll of paper in the operative position;

Fig. 7 is a view similar to Fig. 6 showing the position of the parts when the roll of paper is completely unwound;

Fig. 8 is a view similar to Fig. 6 showing the roll supporting mechanism in a moved position in which the roll core is discharged;

Fig. 9 is a fragmentary view showing the roll carrying arms in the charging position;

Fig. 10 is a section on the line 10—10 of Fig. 9;

Fig. 11 is a section on the line 11—11 of Figure 1;

Fig. 12 is a back view of one roll supporting arm and the roll brake mechanism attached thereto, the brake and brake drum being shown in section;

Fig. 13 is a view similar to Fig. 12 showing the roll supporting arm in the open position preparatory to charging a roll of paper therein;

Fig. 14 is a section on the line 14—14 of Fig. 12 showing the brake drum in elevation;

Fig. 15 is an enlarged view partly in section, showing the mechanism for longitudinally adjusting the roll carrier of the unwind mechanism;

Fig. 16 is a detail partly in section, showing the support for the winder core;

Fig. 17 is a section through the means for longitudinally adjusting the roll carriers of the 5 winding mechanism;

Fig. 18 is an end view of the winder mechanism showing pneumatic means for controlling the pressure between the rolls;

Fig. 19 is a diagrammatic view of the unwinding mechanism showing pneumatic means for controlling the pressure between the rolls and for controlling the brake action, and

Fig. 20 is an enlarged section showing clutch means for driving the air valves.

15 I have herein shown and described the invention as employed with a supercalender, in which it possibly finds its most important use, though it will be understood that such showing is by way of illustration and not limitation, and the 20 invention contemplates use with a wide variety of paper working and similar machines. The super-calender herein shown is of the type having vertical frame members 15 and 16 and horizontal frame members 17 and 18. The calender 25 has a lower roll 19 carried on the frame member 17, a plurality of intermediate rolls 21 carried on the frame members 15 by means of arms 22 and an upper roll 23 carried on the frame members 15 by means of an arm 24. Vertical adjustment 30 of the arms 24 is accomplished through screws 25 which also serve to adjust the position of pressure applying arms 26 positioned at opposite ends of the rolls. Screws 27 pivotally carried on the frame members 18 are driven by means of a 35 motor 28 and act against the arms 26 to drive the same downward against the pressure of springs 29 which bear against brackets 31 on the forward ends of the arms 24 to apply resilient pressure to the calender rolls. It is believed that 40 the foregoing description of the supercalender will be sufficient for an understanding of the present invention, the supercalender per se forming no part of this invention.

Attention is first directed to the winder portion 45 of the device which is similar in many respects to the unwind portion and is the simpler of the two constructions. The winder contemplates broadly winding up the sheet of paper on a roll core directly as it comes from the lower 50 calender roll, the roll of paper being wound having direct surface contact with the calender roll and being driven thereby. The structure contemplates means for rotatably supporting the roll of paper in this position and for subsequently 55 moving the roll into a discharge position, together with means for discharging the roll from the winder in the discharge position. The mechanism also includes means for controlling the pressure of the roll of paper against the calender 60 roll so as to regulate the tightness with which the sheet is rolled, or, in other words, the hardness of the roll of paper.

As will be seen from Fig. 2, a shaft designated 65 generally by the numeral 33 extends transversely across the calender parallel to the lower roll 19 thereof, and has a central rectangular portion 34 and cylindrical portions 35 and 36 at its ends. The cylindrical portion 35 is rotatably carried in an upwardly extending bracket 37 supported on 70 a base 38 attached to one of the frame members 17, the bracket being held on the base by means of angle members 39 and 41 which form ways in which the bracket may swivel slightly relative to block 38. The bracket also receives a pin 40 75 which extends upward from the frame member

11, through the base and into the bracket, the pin serving to position the bracket and permitting a certain amount of angular movement of the bracket in the ways during lateral adjustment of the shaft, as will presently be described. 5 The cylindrical portion 36 is carried in a bearing 42 attached to a base 43 by means of angle members 44 and 45 which form ways for the adjustment of the bearing laterally so as to adjust the alignment of the shaft 33 relative to the calender 10 roll. Adjustment is accomplished by means of a screw 46 abutting at its ends against abutments 47 and 48, and having threaded engagement with the bearing 42 and carrying a nut 49 or other means for turning the screw. Positioned 15 on the rectangular portion 34 of the shaft are sleeves 51 and 52 slidably received on the shaft and carrying upwardly extending arms 53 and 54. On the outer end of the arms 53 and 54 are bearings 55 and 56, carrying stub shafts 57 and 20 58 for reception in the ends of a winder core 59. Pins 60 on the shafts are received in slots 60a of the core to establish driving connection therebetween. Bands 60b of rubber or similar resilient material may encircle the shafts 57 and 58 25 for resilient contact with the calender roll though this is by no means essential. The winder core 59 is, therefore, rotatably carried on the arms 53 and 54 through the bearings 55 and 56, and is adapted to be driven by contact of the 30 core or of the roll of paper thereon against the lower roll 19 of the calender stack.

The winder core 59 is positioned on and removed from the shafts 57 and 58 by movement of the arms 53 and 54 toward and away from 35 each other on the rectangular portion 34 of the shaft, the sleeves 51 and 52 moving on the shaft to accomplish this purpose. To accomplish movement of the arms 53 and 54, internally threaded nuts 61 and 62 are positioned on the 40 arms 53 and 54, respectively, and serve to receive a rod 63 threaded adjacent its opposite ends, as shown at 64 and 65. The rod 63 has bearing support in a bearing 66 carried on the rectangular portion 34 of the shaft, which bearing also serves 45 to take end thrust on the rod 63. The threaded portions 64 and 65 are so pitched that upon rotation of the rod 63 in one direction, the arms will move away from each other so as to release the core 59, and upon rotation of the rod in the opposite direction, the arms will be brought together for insertion of the core. In this manner the arms are movable between an open and a closed position. To accomplish rotation of the rod 63, a motor 67 carries a gear 68 meshing with 55 a gear 69 arranged to drive the rod through a friction clutch 71, the clutch being arranged to slip under excessive load such as results from the arms 53 and 54 reaching their closed position. The motor 67 is carried on a collar bracket 72 attached to the end of the shaft 33 by means of collar 73 keyed and clamped on the shaft. Likewise, the gear 69 is carried in a bearing 74 on a collar 75 keyed and clamped to the shaft 33. On the opposite end of the rod 63 from the clutch 71 60 is a nut 76 adapted to contact the nut 61 of the arm 53 to prevent the arm from being run completely off the rod.

The rotative movement of the shaft 33 is controlled through a gear segment 77 keyed to the 70 end 35 of the shaft and arranged to mesh with a pinion 78 on a shaft carried in a bearing 79 on the upper end of the bracket 37. The opposite end of the shaft carries a gear 81 arranged to mesh with a pinion 82 carried on a shaft 83 supported 75

in a bearing 80 on the bracket 37. The shaft 33 carries a wheel 84 for manual rotation thereof and a drum 85 over which a cable 86 is trained, the cable carrying suitable weights 87. The cable 86 is shown in the drawings as being trained on the drum in a direction such that its weight tends to press the core against the bottom calender roll 19 but it may also be trained in the opposite direction to obtain a counterbalancing action when desired to produce the proper winding characteristic. The weight of the arms and of the core together with the remaining part of the mechanism carried on the shaft 33 is such that, it is not normally sufficient to give the desired pressure between the core and bottom calender roll 19 when starting. By varying the amount of the weight 87, any desired pressure may be obtained between the core or the roll of paper mounted thereon and the calender roll. A change in the amount of pressure may also be automatically obtained by employing an eccentrically mounted drum. The invention also contemplates pneumatic or similar means for regulating the pressure as the roll builds up, as will presently be described.

Longitudinal adjustment of the core 59 and its supporting elements are required in order that the emerging paper may be caused to wind correctly between the ends of the core. This is accomplished by shifting the shaft 33 together with the elements carried thereon. A stud 88 (Fig. 17) is threaded and pinned into the end 35 of the shaft 33 and passes through a sleeve 88a. Collars 88b and 88c retain the sleeve on the stud, the latter being capable of free rotation in the sleeve. The sleeve is threaded on the outside as shown at 88d for reception in a bracket 91 having an internally threaded opening, the bracket being split and provided with a bolt 92 to clamp the bracket onto the sleeve. The sleeve has a collar 89 with radial holes in it for rotation thereof in the bracket to move the shaft 33 endwise. The stud 88 is, however, rotatable independently of the sleeve with the shaft.

The various steps in the operation of the device are graphically shown in part in Figs. 3-5, inclusive. When paper is to be wound onto the core 59, the parts are brought into the position shown in Fig. 3 with the core held between the arms 53 and 54, and the core in contact with the lower calender roll 19. At this point if the lower calender roll and the core 59 are not in complete parallelism, the position of the bearing 42 is adjusted through operation of the screw 46. When the core has been adjusted into parallelism with the roll and to a longitudinal position to properly receive the paper from the calender stack, the device is effective to roll the paper emerging from the calender directly onto the core 59, the core rotating through contact with the calender roll. As previously set forth, the weights 87, which may be varied at the will of the operator, serve to regulate the pressure of the roll of paper against the calender roll and thereby regulate the tightness or hardness of the paper roll. As the roll of paper becomes larger and larger, the parts move into the position shown in Fig. 4. When the paper roll has reached the desired size, the sheet of paper is severed and, through operation of the hand wheel 84, the arms 53 and 54, together with the roll of paper carried thereon, is moved to the position shown in Fig. 5, the roll of paper being deposited on a truck or similar transporting device located in front of the winder. Thereupon the motor 67 is operated in a direction to move the

arms 53 and 54 to their open position, discharging the roll from the winder. Another core is then held in proper position and the motor 67 is operated in the opposite direction to bring the arms to the closed position to charge the empty core. Operation of the hand wheel 84 again brings the parts into the position shown in Fig. 3 for the winding of a further roll.

In Figs. 2-5, I have shown a form in which the weight 87 acts uniformly throughout its movement. In other words, the weighting effect of the weights 87 on the shaft 33 is uniform. This condition may be altered by manually changing the amount of the weights 87 during the winding of a roll, but I have provided remote control means for accomplishing this. A piston rod 81a (Fig. 18) is pivotally attached to the weight 87, and carries a piston 81b within a cylinder 81c having outlets 81d and 81e controlled by valves 81f and 81g and inlets 81h and 81i provided with valves 81j and 81k and a pressure gauge 81m for indicating the pressure on either side of the piston. The piston is preferably pneumatically operated and serves to either increase or decrease the tension on the cable 86 over that provided by the weight 87. The valves are arranged to be controlled by the operator from a point otherwise convenient in the operation of the machine and through the manipulation thereof he is enabled to change the pressure between the roll of paper and the calender roll at will during the winding of a roll.

The unwind mechanism operates on substantially the same principle as the winder mechanism just described, and includes a shaft 93 (Fig. 11) of rectangular cross-section throughout a substantial portion of its length and having spaced cylindrical portions 94 and 95, a central rectangular portion 96, rectangular portions 97 and 98, and cylindrical portions 99 and 101. The cylindrical portions 99 and 101 at opposite ends of the shaft are carried in bearings 102 and 103 for rotation therein and for longitudinal movement of the shaft. The bearings 102 and 103 are carried on plates 104 and 105 attached to the pressure applying arms 26 of the supercalender. The bearing 102 is attached to the plate 104 by angle members 106 and 107 within which the bearing is movable to shift the shaft 93 laterally, movement of the bearing being brought about by means of a screw 108 threaded in the bearing and bearing at its ends against abutments 109 and 111, attached to plate 104, the screw having a nut 112 or other means for manually rotating the same. The bearing 103 is fixed to the plate 105 by means of angle members 113 bolted thereto. The shaft 93 is adjustable longitudinally in order to cause the paper to feed into the calender in the proper area between the ends of the calender roll. A stud 114, (Fig. 15) is threaded and pinned into the end 101 of the shaft 93, the stud having a bead 114a and a nut 114b threaded and pinned thereon. An externally threaded sleeve 110 is positioned on the stud between the head and the nut and is threaded into a bearing member 115. The sleeve 110 carries an internally splined member 110a for cooperation with a toothed member 116a driven from a motor 116 through a gear box 116b. The motor and the bearing member 115 are attached to a plate 118 integral with the bearing 103, whereby these parts may turn as a unit about a pin 117 extending between the plates 105 and 118 upon lateral adjustment of the opposite end of the shaft 93.

Thus the shaft is arranged for longitudinal

adjustment, and the bearing 102 is arranged for lateral adjustment to adjust the position of the shaft 93 with respect to the upper roll of the supercalender. Arms 119 and 121 are integral with sleeves 122 and 123 carried on the rectangular portions 97 and 98 of the shaft, the sleeves being movable longitudinally thereof. Threaded nuts 124 and 125 are carried on the sleeves 122 and 123 and receive a rod 126 threaded 5 at its ends as shown at 127 and 128 for reception in the nuts 124 and 125. A combined radial and thrust bearing 129 on the shaft 93 supports the rod 126 and prevents longitudinal movement thereof. The rod 126 is driven from a motor 131 10 through gears 132 and 133 and a safety friction clutch 134, the motor 131 being operable in either direction to move the arms 119 and 121 toward and away from each other selectively. The motor 131 and the gear 133 are carried on the ends of the 15 shaft 96 by means of collars 135 and 136 keyed and clamped on the shaft. A nut 137 on the end of the rod 126 opposite the clutch serves to prevent the end of the rod 126 from being screwed completely out of the nut 125.

20 25 The outer ends of the arms 119 and 121 carry bearings 138 and 139 such as shown in Fig. 10, each of the bearings having a shaft 141 provided on its outer end with a collar 142 forming a socket 143, the socket having a cross pin 144. 30 The sockets 143 are adapted for the reception of the ends 145 of spools designated generally by the numeral 146. Thus, through operation of the motor 131, the arms 119 and 121 are moved between a closed position as shown in Figs. 10 and 35 40 45 50 55 60 65 70 75 80 85 90 95 100 105 110 115 120 125 130 135 140 size and position of the paper roll as the unwinding operation proceeds, or to impart other desired unwinding characteristics. The chains 172 serve to draw the paper roll against the calender roll 5 and maintain the rolls in desired relative relation. It will be seen that by altering the size of the drum 177 and its eccentricity on the shaft 175, any desired measure relationship between the paper roll and the calender roll may be had. 10 The invention also contemplates fluid means for automatically regulating the pressure between the rolls in response to the position of the arms, pneumatic means being shown diagrammatically in Fig. 19. The drum 177 may be concentric on 15 the shaft 175 or may be eccentric dependent upon the unwinding characteristics desired. In this instance I have shown the drum concentric. The shaft 175 is provided with a sprocket 177a over which a chain 177b is trained to drive a sprocket 177c on a shaft 177d. The latter carries a beveled gear 177e cooperating with a bevel gear 177f on a vertical shaft 177g. The shaft 177g is connected to a pressure regulator 177h through 20 clutch means shown in Fig. 20 including a hand wheel 177i carried on the stem of the regulator, the wheel having a hub faced for frictional engagement with a friction disk 177j keyed on the shaft 177g for longitudinal movement with respect thereto. A spring 177k normally urges the 25 friction disk against the hand wheel to cause the same to be driven by the shaft 177g but permitting the regulator to be manually adjusted with respect to the shaft through the hand wheel 177i. The regulator controls the air pressure to a cylinder 177m, valved pipes 177n permitting the air to 30 be applied against either end of a piston 177o positioned in the cylinder. A pressure gauge 177p serves to indicate the pressure applied to the cylinder, while valved pipes 177r serve selectively to permit egress of air from either end 35 of the piston. The piston 177o is pivotally attached to the bottom of weights 179 by means of a piston rod 177s and a connection 177t. Thus, as the paper is unrolled and the roll of paper 40 decreases in radius, the arms 119 and 121 move in a counterclockwise direction causing rotation of the shaft 175 and sprocket 177a, which in turn causes alteration of the air pressure in the cylinder 177m, thereby increasing or decreasing the 45 effect of the weights 179 on the roll of paper to alter the pressure between the rolls as desired in response to movement of the roll of paper. By 50 altering the size and eccentricity of the drum 177, any desired unwinding characteristics may 55 be obtained.

Referring now more particularly to the means for swinging the arms 119 and 121, and the paper roll 148 carried thereon, between the various rotative positions thereof involving the charging 60 position in which the roll of paper is charged into the unwind mechanism, the unwinding position and the spool discharging position in which the spool is discharged from the arms, Fig. 6 shows the parts at the time when the unwinding 65 of the paper roll has just begun, Fig. 7 shows the parts in the position occupied when the paper is substantially entirely unwound. Fig. 8 shows the parts in a position to discharge the empty spool, and Fig. 9 shows the arms in the position 70 to charge a fresh roll of paper.

Assuming the parts to occupy the positions showing in Fig. 6 rotation of the arms is accomplished by means of chains 181 attached to the opposite sides of arms 119 and 121 as shown at 75 182 and trained over sprockets 183, 184, 185, 186,

187 and 188. Tighteners operate against the chains between the sprockets 184 and 185 and consist of brackets 189 on the frame members 18 upon which arms 191 are pivotally supported, as shown at 192, the arms carrying sprockets 193 5 adapted to engage the upper side of the chains 181 and carrying weights 194 adjustably positioned on the arms 191 to vary the weight on the chain. The sprockets 187 are carried on a shaft 195 extending transversely of the calender and 10 driven by means of a motor 196. Weights 197 on the ends of the chains serve to maintain the chains in contact with the sprockets 187 and 188. It will be seen that when the motor is operated in one direction, the arms 119 and 121 are moved 15 in a clockwise direction viewing Fig. 8, and when the motor is operated in the opposite direction, the arms are allowed to rotate in a counterclockwise direction into the position shown in Fig. 6, this rotation of the arms occurring under the 20 weight of the parts and the action of the chains 172. When the roll of paper contacts the calender roll, continued operation of the motor 196 develops slack in the chains 181 which is taken up by the chain tighteners under the action of 25 the weights 194. This slack permits of continued movement of the arms toward the calender roll as unwinding proceeds to maintain the roll of paper in surface contact therewith as the size of the roll decreases during unwinding. The rolls 30 of paper are charged into the roll carriers through roll lifting and positioning means which serves to bring a roll of paper into the charging position and to maintain the roll in alignment for reception on the arms. This consists of means 35 for lifting the roll and gauge means for guiding the roll into the charging position.

Gauge arms 198 and 199 (Figs. 8 and 11) are fixedly connected to a rod 201, and are pivotally carried on the shaft 93 by means of bearings 202 40 and 203. The gauge arms have fingers 204 and 205 projecting laterally outward in a position to be contacted by the arms 119 and 121, the fingers carrying adjusting screws 206 and 207 for contact with the arms 119 and 121 for a purpose which will presently appear. Lower position of these 45 gauge arms is determined by chains 208 and 209 carried on brackets 211 and 212 on the frame members 18, the chains being connected to the fingers 204 and 205 as shown in Fig. 11. The outer ends of the gauge arms are each provided 50 with a slot 213 (Fig. 6) having tapered edges 214 (Fig. 10) for reception in complementary shaped grooves 215 on the paper spool 146. A roll lifting device (Fig. 8) consists of a pair of side pieces 55 216 spaced for the reception of a roll 217 therebetween and connected at their ends as shown at 218, the transverse connecting member carrying an eyelet 219 adapted to receive the hook of a hoist cable 221 for the purpose of hoisting the 60 roll into position. Each of the side pieces 216 are curved as shown at 222 to provide a cradle for the reception of the projecting end of the paper spool 146, the spool having an annular recess 65 223 for the reception thereof. The lower ends of the side pieces 216 each have a hook 224 also adapted to be received in the recesses 223 of the spool. The roll 217 is raised upward by the hoist cable 221 until the slots 213 of the gauge arms are received in the grooves 215 of the paper spool, 70 the guide arms with their slots and the complementary grooves on the spool serving to position the spool and associated roll in the charging position.

The operation of the unwind mechanism is as 75

follows: Assuming the parts to be in the position shown in Fig. 6, the roll of paper 148 is pressed against the upper calender roll 23 by means of the chains 172, the paper roll being driven by contact with the calender roll and the sheet of paper being transferred from the paper roll to the calender roll at the nip between these rolls. The speed of rotation of the paper roll is retarded by the action of the brake chain 150, the action of this chain and of the drum 177 and weight 179 regulating the tension of the paper sheet as it enters the calender. When the paper roll 148 has been completely unwound, the parts will have assumed the positions shown in Fig. 7 with the spool bearing directly against the calender roll, the arms 119 and 121 having moved to compensate for the reduction in size of the paper roll. This movement is permitted through the slack in the chains 181, the tightener sprockets 193 maintaining the chain taut, and the tightener moving upward with such movement of the arms. During the unwinding of the roll 148, the operator brings a fresh roll of paper into charging position in front of the machine.

25 When the paper is entirely unwound from the roll 148 and the parts reach the position shown in Fig. 7, the motor 196 is operated in a direction to draw the arms 119 and 121 into the position shown in Fig. 8 with the recesses 223 of the spool abutting the end pieces 216 of the lifting device. The motor 131 is then operated to move the arms 119 and 121 to the open position, whereupon the empty spool is discharged into the hooked ends 224 of the side pieces 216. The motor 196 is then again operated to draw the arms 119 and 121 into the position shown in Fig. 9, that is, until the arms 119 and 121 abut the adjusting screws 206 and 207. The motor 196 is then stopped. The arms 119 and 121 are then in a position for the ends 145 of the loaded spool to be received in the sockets 143 (Fig. 10). The motor 131 is then operated in the opposite direction to bring the roll carrying arms into the closed position engaging the ends of the spool.

45 After this the roll-lifting device is lowered away from the roll, leaving the roll supported on the arms 119 and 121. The motor 196 is then operated to permit the roll to drop into the position shown in Fig. 6 and is allowed to run a sufficiently greater length of time to provide suitable slack in the chain 181 so that the tighteners drop to the position shown in Fig. 6. The sheet from the new roll of paper is then threaded through the calender and the calender is again brought into operation.

60 While the manifold advantages of my improved winding and unwinding mechanism will doubtless have become apparent, I desire to direct particular attention to a number of the more important features. The long draws between the paper working machine and the winders or unwinders, which have heretofore been necessary, are entirely eliminated and the sheet is supported by a roll at all times while being transferred between the rolls of the paper working machine and the roll of paper. Because of the surface contact of the winding or unwinding rolls with the rolls of the paper machine, a considerable amount of mechanism is eliminated. For instance, the 70 dance rolls are entirely eliminated as are the devices employed for maintaining uniformity in the tension between calenders and the like and the winding mechanism. Likewise, the difficulty attending the synchronizing of the speed of the winder and of the paper making or treating ma-

chine is entirely eliminated, the winder roll being driven directly by surface contact with the roll of the calender or of the machine.

I also desire to direct attention to the compactness of the winder and unwinder. As will be seen from Figure 1, the mechanism when attached to a supercalender occupies but little more floor space than that required for the supercalender itself. Another advantage lies in the ease of charging and discharging the machine and in the speed with which these operations may be accomplished. It will be seen that the roll may be discharged from the winder by a simple operation of the hand wheel 84, the wound roll being deposited directly on a truck or other means for conveying the roll. Likewise, the rolls are easily and quickly charged into the unwinding mechanism, and a second roll may be brought into its charging position while the first roll is being unwound so that the only time consumed in changing the roll is that required to move the arms between their various positions.

Means are provided which are automatically operable to control the pressure between the roll of paper and the calender roll and to vary the pressure accordingly to certain preconceived requirements. Control means serve to automatically regulate the braking action on the unwinding roll, in response to the decrease in size of the roll of paper.

I have shown and described a particular embodiment of the invention for purposes of illustration, but I am aware that numerous alterations and changes may be made within the spirit of the invention, and do not wish to be limited except as required by the prior art and the scope of the appended claims, in which I claim:

1. In combination with a supercalender having upper and lower rolls, of winding and unwinding mechanism comprising rotatably supported frames adjacent said calender rolls, means on each of said frames for rotatably supporting a roll of paper in surface contact with the adjacent calender roll for the transfer of a paper sheet therebetween, means for charging a roll of paper into one of said frames to supply paper to the supercalender, and means to discharge the wound rolls of paper from the other frame.

2. The combination with a supercalender having upper and lower rolls, of winding and unwinding mechanism comprising rotatably supported frames adjacent said calender rolls, means on each of said frames for supporting a roll of paper for rotation in surface contact with the adjacent calender roll to transfer a paper sheet therebetween, means for regulating the pressure between said rolls of paper and said calender rolls, means for charging a roll of paper into one of said frames for passage through the supercalender and onto the roll of the other of said frames, and means for discharging the wound roll from the said other frame.

3. The combination with a supercalender having upper and lower calender rolls, of a pair of rotatably supported arms adjacent each of said calender rolls adapted to support rolls of paper at their ends in surface contact with said calender rolls to be driven thereby, means for rotating said arms into and out of operative position to bring said rolls of paper into and out of surface contact with said calender rolls, and means for moving said arms to release said rolls of paper when the arms are out of the operative position whereby to charge a roll of paper into

one pair of said arms and discharge a roll of paper from the other pair of said arms.

4. The combination with a supercalender having upper and lower rolls, of a pair of rotatably supported arms adjacent each of said calender rolls adapted to support rolls of paper at their ends in surface contact with said calender rolls to be driven thereby, means for regulating the pressure between said rolls of paper and said calender rolls, and means for moving said arms to release said rolls of paper when said rolls of paper are out of contact with the calender rolls, whereby to charge a roll of paper into one pair of said arms and discharge a roll from the other pair of said arms.

5. The combination with a supercalender having a pair of calender rolls, of winding and unwinding mechanism comprising rotatable arms adjacent said upper roll for holding a roll of paper to be run through the calender, rotatable arms adjacent the lower roll for holding a roll of paper emerging from the calender, said arms being arranged to hold the rolls of paper in surface contact with the calender rolls to be driven thereby, means to move the arms to a position with the rolls of paper out of contact with said calender rolls, and means for moving said arms to charge and discharge the rolls of paper therefrom.

6. The combination with a supercalender having a pair of calender rolls, of winding and unwinding mechanism comprising rotatable arms adjacent said upper roll for holding a roll of paper to be run through the calender, rotatable arms adjacent the lower roll for holding a roll of paper emerging from the calender, said arms for the lower roll being arranged to hold the roll of paper in surface contact with the calender roll to be driven thereby, means to move the arms to a position with the rolls of paper out of contact with said calender rolls, means for moving said arms to charge and discharge the rolls of paper therefrom, and means for positioning a roll of paper for reception on the arms adjacent the upper calender roll upon charging movement of said arms.

7. The combination in a supercalender having upper and lower rolls, of winding and unwinding mechanism comprising upper and lower frames rotatably supported adjacent said rolls, means on each of said frames for rotatably supporting a roll of paper in surface contact with the adjacent calender roll for the transfer of a sheet of paper therebetween, means for rotating said upper frame between its position with said roll of paper in surface contact with the adjacent calender roll, a roll discharging position and a roll charging position, means for positioning a roll of paper in a position to be charged into said frame in the charging position thereof and for receiving the roll discharged therefrom in the discharge position thereof, means to move said supporting means to discharge and charge a roll of paper, and means to discharge a roll of paper from said lower frame.

8. The combination in a supercalender having upper and lower rolls, of winding and unwinding mechanism comprising upper and lower frames rotatably supported adjacent said rolls, means on each of said frames for rotatably supporting a roll of paper in surface contact with the adjacent calender roll for the transfer of a sheet of paper therebetween, means for rotating said upper frame between its position with said roll of paper in surface contact with the adjacent

calender roll, a roll discharging position and a roll charging position for charging, unwinding and discharging a roll of paper, and means to discharge a wound roll of paper from said lower frame.

9. The combination in a supercalender having upper and lower rolls, of winding and unwinding mechanism comprising upper and lower frames rotatably supported adjacent said rolls, means on each of said frames for rotatably supporting a roll of paper in surface contact with the adjacent calender roll for the transfer of a sheet of paper therebetween, means for rotating said upper frame between its position with said roll of paper in surface contact with the adjacent calender roll, a roll discharging position and a roll charging position, means for positioning the roll of paper in a position to be charged into said frame in the charging position thereof, means to move said supporting means to discharge and charge a roll of paper therein, and means to discharge a wound roll of paper from said lower frame.

10. The combination with a supercalender having a calender roll of winding mechanism comprising a frame rotatably positioned along one side of said roll, means on the frame for supporting a roll of paper upon which a sheet of paper is being wound with the roll of paper in surface contact with said calender roll, manually operable means for moving the frame and the roll of paper to a discharge position remote from the calender roll, and motor driven means carried on the frame for discharging said roll of paper and for charging a core upon which a subsequent roll is to be wound.

11. The combination with a supercalender having a calender roll of winding mechanism comprising a frame rotatably positioned along one side of said roll, means on the frame for supporting a roll of paper upon which a sheet of paper is being wound with the roll of paper in surface contact with said calender roll, manually operable means for moving the frame and the roll of paper to a discharge position remote from the calender roll, motor driven means carried on the frame for discharging said roll of paper and for charging a core upon which a subsequent roll is to be wound, and manually variable weights arranged to act on said manually operable means to control the pressure between the roll of paper and the calender roll and thereby determine the tension of the paper in said paper roll.

12. The combination in a paper working machine having a paper working roll, of unwinding mechanism comprising a shaft positioned to one side of the vertical center line of said paper working roll, a pair of depending arms on said shaft for supporting a roll of paper to be fed to said machine, weights arranged to urge the roll of paper against the paper working roll to maintain said roll of paper in surface contact with said paper working roll to transfer the sheet of paper between the rolls in the area of contact, the roll of paper being driven through said contact, means for automatically and progressively varying the effect of the weights upon the roll during the unwinding of a roll to regulate the pressure between the roll of paper and the paper working roll.

13. The combination in a paper working machine having a paper working roll of unwinding mechanism comprising a shaft located to one side of the vertical center line of said roll, a pair of depending arms on said shaft for supporting a roll of paper to be fed to said machine, weights arranged to urge the roll of paper into surface

- contact with the paper working roll to transfer a sheet of paper from the roll of paper to the paper working roll in the area of contact, means for automatically and progressively varying the 5 effect of the weights upon the roll of paper to regulate the pressure between the roll of paper and the paper working roll, and brake means acting on the roll of paper to retard the rotation thereof.
- 10 14. The combination with a paper working machine having a paper working roll of unwinding mechanism comprising roll carriers located adjacent the ends of said paper working roll arranged to support a spool of paper in surface contact with said paper working roll to transfer a sheet of paper from the spool of paper to the paper working roll in the area of contact, means for rotating said roll carriers to transport said spool of paper to a point remote from said paper 15 working roll, means for moving said roll carriers toward and away from each other to discharge an empty spool and to charge a subsequent spool of paper, and guide means to predetermine the position of said subsequent spool of paper for 20 reception on said roll carriers when the carriers are moved toward each other.
- 15 15. In a paper working machine having a paper working roll, and means for supporting a roll of paper in surface contact therewith for feeding 30 paper to said paper working roll, the combination therewith of pneumatic means automatically operable in response to a change in size of said roll of paper to control the pressure between said rolls.
- 35 16. In a paper working machine having a paper working roll, and means for supporting a roll of paper in surface contact therewith for feeding paper to said paper working roll, the combination therewith of weight means for moving the roll of 40 paper toward the roll of said machine to apply pressure between said rolls, and pneumatic means operable in response to a change in the size of said roll of paper to progressively control the pressure between the rolls during the feeding of a roll of paper.
- 45 17. In a paper working machine having a paper working roll, and means for supporting a roll of paper in surface contact therewith for feeding paper to said paper working roll, the combination therewith of weight means for moving the roll of paper toward the roll of said machine to apply pressure between said rolls, a pneumatic piston 50 operable on the weight means, means driven in response to a change in size of said roll to vary the pressure on said piston to control the pressure between said rolls, and means to vary the pressure on said piston independently of the size of said roll of paper.
- 55 18. In a paper working machine having a paper working roll, and means for supporting a roll of paper in surface contact therewith for feeding paper to said paper working roll, the combination therewith of weight means for moving the roll of paper toward the roll of said machine to apply pressure between said rolls, and means acting on 60 said weight selectively operable to increase or decrease the effective weight thereof.
- 65 19. In a paper working machine having a paper working roll, and means for supporting a roll of paper in surface contact therewith for feeding paper to said paper working roll, the combination therewith of weight means for moving the roll of paper toward the roll of said machine to apply pressure between said rolls, means acting on said 70 weight selectively operable to increase or decrease the effective weight thereof, and means responsive to a change in size of said roll of paper to progressively change the amount of said increase or decrease.
- 75 20. In a paper calender having a paper working roll, and means for supporting a roll of paper in surface contact therewith for feeding paper to said roll, the combination therewith of brake means for retarding the rotation of said roll of paper to control the tension of the paper, and pneumatic means for controlling the brake, automatically operable in response to movement of said supporting means to progressively decrease the effect of the brake on the roll of paper.
21. The combination in a supercalender having upper and lower rolls, of winding and unwinding mechanism, comprising rotatably supported frames adjacent said calender rolls, means on each of said frames for rotatably supporting a roll of paper adjacent said roll for transfer of a paper sheet therebetween, means for providing a predetermined surface pressure between one of said rolls of paper and the lower calender roll, means for charging a roll of paper into one of said frames to supply paper to the supercalender, and means to discharge the wound rolls of paper from the other frame.
22. The combination with a supercalender having upper and lower calender rolls, of a pair of rotatably supported arms adjacent each of said calender rolls adapted to support rolls of paper at their ends adjacent said calender rolls to be driven thereby, means for rotating said arms into and out of operative position to bring said roll of paper into and out of winding and unwinding relation with said calender roll, and means for moving said arms to release said rolls of paper when the arms are out of the operative position whereby to charge a roll of paper into one pair of said arms and discharge a roll of paper from the other pair of said arms.
23. The combination with a supercalender having upper and lower calender rolls, of winding and unwinding mechanism comprising rotatable unwinding arms adjacent said upper roll for holding a roll of paper to be run through the calender, rotatable winding arms adjacent the lower roll for holding a roll of paper emerging from the calender, said winding arms being arranged to hold the roll of paper in surface contact with the calender roll to be driven thereby, means to move the winding arms to a position with the roll of paper out of contact with said calender roll, and means for moving said winding and said unwinding arms to charge and discharge the roll of paper therefrom.
24. The combination with a supercalender having upper and lower calender rolls, of winding and unwinding mechanism, comprising rotatable unwinding arms adjacent said upper roll for holding a roll of paper to be run through the calender, rotatable winding arms adjacent the lower roll for holding a roll of paper emerging from the calender, said winding arms being arranged to hold the roll of paper in surface contact with the calender roll, means to move the winding arms to a position with the roll of paper out of contact with said calender roll, means for moving said winding and unwinding arms to charge and discharge the roll of paper therefrom, and means for positioning a roll of paper for reception on the unwinding arms upon charging movement thereof.
25. The combination in a supercalender having upper and lower calender rolls, of winding and

- unwinding mechanism, comprising upper and lower frames rotatably supported adjacent said rolls, means on each of said frames for rotatably supporting the roll of paper adjacent said calender rolls for the transfer of a sheet of paper therebetween, means for rotating said upper frame between an unwinding position adjacent said calender roll, a roll discharging position and a roll charging position, means for positioning a roll of paper in a position to be charged into said frame in the charging position thereof and for receiving the roll discharged therefrom in the discharge position thereof, means to move said supporting means to discharge and charge a roll of paper, and means to discharge a roll of paper from said lower frame.
26. The combination in a supercalender having upper and lower calender rolls, of winding and unwinding mechanism comprising upper and lower frames rotatably supported adjacent said rolls, means on each of said frames for rotatably supporting a roll of paper adjacent said calender roll for the transfer of a sheet of paper therebetween, means for rotating said upper frame between its position adjacent the calender roll, a roll discharging position and a roll charging position for unwinding, discharging and charging a roll of paper, and means to discharge a wound roll of paper from said lower frame.
27. The combination in a supercalender having a calender roll, of unwinding mechanism comprising a shaft positioned to one side of the vertical center line of said calender roll, a pair of depending arms on said shaft for supporting a roll of paper to be fed to said machine, weights arranged to urge the roll of paper toward the calender roll to an unwinding position for the transfer of the sheet of paper between the rolls, means for automatically and progressively varying the effect of the weights upon the roll during the unwinding of the roll, and brake means acting on the roll of paper to retard the rotation thereof.
28. The combination with a supercalender having a calender roll of unwinding mechanism comprising roll carriers located adjacent the ends of said calender roll arranged to support a spool of paper in an unwinding position adjacent said calender roll to transfer a sheet of paper from the spool to the calender roll, means for rotating said roll carriers to transport said spool of paper to a point remote from said calender roll, means for moving said roll of carriers toward and away from each other to discharge an empty spool and to charge a subsequent spool of paper, and guide means to predetermine the position of said subsequent spool of paper for reception on said roll carriers when the carriers are moved toward each other.
29. The combination with a supercalender, of means for feeding paper thereto, comprising a frame located adjacent the upper roll thereof adapted to rotatably support a roll of paper adjacent the upper roll of said machine for the transfer of a paper sheet therebetween, said frame having a pair of supporting arms movable toward and away from each other to receive and discharge the paper roll, a prime mover carried on said frame for moving said arms, and power operating means for adjusting the longitudinal position of said frame to predetermine the area in which the sheet enters the calender roll.
30. The combination with a supercalender, of means for feeding paper thereto, comprising a frame located adjacent the upper roll thereof adapted to rotatably support a roll of paper adja-
- cent the upper roll thereof for the transfer of paper sheet therebetween, said frame having a pair of supporting arms movable toward and away from each other to receive and discharge a paper roll, weight means for urging said frame in one direction, power means for moving the frame in the opposite direction from an unwinding position adjacent the roll of said machine to an unloading position and thence to a loading position, a loading frame having spaced side arms providing roll and spool sockets, said loading frame being adapted to be lifted to a charging position, means on said frame for locating said loading frame to predetermine the charging position thereof, and means for moving the supporting arms away from each other in the discharging position thereof to deposit the empty spool in said spool socket and moving said arms toward each other in the charging position thereof to receive a roll from said roll socket.
31. The combination with a supercalender of means for feeding paper thereto, comprising a frame adapted to rotatably support a roll of paper adjacent the upper roll of said machine for the transfer of paper sheet therebetween, said frame having a pair of supporting arms movable toward and away from each other to receive and discharge the paper roll, spindles on said arms to support the roll of paper thereon, a prime mover carried on said frame for moving said arms, power operated means for adjusting the longitudinal position of said frame to predetermine the area in which the sheet enters the calender roll, a brake carried on said frame and movable therewith, and means for transmitting the braking action thereof to one of said spindles to retard the rotation of said roll of paper.
32. The combination with a calendering machine, of means for supporting a roll of paper in surface contact with an operation roll of said machine to transfer paper therebetween, fluid brake means for retarding the rotation of said roll of paper, and means for controlling the supply of fluid to said brake means in response to change in the diameter of the paper roll to regulate the tension on the paper.
33. The combination with a calendering machine, of means for supporting a roll of paper in surface contact with an operation roll of said machine to transfer the sheet of paper therebetween, fluid operated means for exerting pressure between said operation roll and said roll of paper to regulate the tension on the paper, and means automatically responsive to the change in diameter of said roll to control said last mentioned means.
34. The combination with a calendering machine, of a winder comprising a frame rotatably supported adjacent an operation roll of said machine and to one side thereof, means on the frame for rotatably supporting a roll of paper at its ends in contact with said machine roll and in a position to receive the paper therefrom and be driven thereby, the weight of said means and said frame being disposed to apply pressure between the roll of paper and said machine roll, and a pneumatic piston selectively operable on said frame to counterbalance the weight of said supporting means, said frame, and said roll of paper or add to the effective weight thereof to produce any desired pressure between the roll of paper and the machine roll to regulate the tightness of the paper being wound.
35. The combination with a supercalender having a calendering roll of unwinding mecha-

nism comprising roll carriers located adjacent the ends of said calendering roll arranged to support a spool of paper adjacent said calendering roll to transfer a sheet of paper from the spool of paper to the paper working roll, means for supporting said roll carriers, motor driven means for adjusting the longitudinal position of the last mentioned means with respect to said calendering rolls, motor driven means for rotating said roll carriers to transport said spool of paper to a point remote from said paper working roll, and motor driven means for moving said roll carriers toward and away from each other to discharge an empty spool and to charge a subsequent spool of paper.

36. The combination in a calender having a calendering roll of unwinding mechanism comprising roll carriers arranged to support a spool of paper adjacent said calendering roll to feed said paper to the calender, a fluid brake for controlling the rotation of said spool, valve means

for controlling the supply of fluid to the brake, means for operating said valve in response to changes in position of said roll carriers to progressively adjust the operation of the brake through a cycle, and manually operable means to operate said valve to change the cycle. 5

37. The combination in a calender of unwinding mechanism comprising depending arms for supporting a roll of paper to be fed to said calender, flexible means attached to opposite sides 10 of said arms to move the latter between an operative position adjacent a calender roll and a discharge position remote therefrom, a motor for driving one of said flexible means to move said arms to said discharge position, and weight 15 means for driving the other of said flexible means to move said arms to the operative position.

CHARLES P. PUTNAM.
